UNITED STATES PATENT OFFICE.

EDGAR D. HEGAMIN, OF ST. LOUIS, MISSOURI

FLOWER-HOLDER.

1,379,340.

Specification of Letters Patent. Patented May 24, 1921.

Application filed January 7, 1921. Serial No. 435,680.

To all whom it may concern:

Be it known that I, EDGAR D. HEGAMIN, a citizen of the United States, residing in the city of St. Louis and State of Missouri, 5 have invented certain new and useful Improvements in Flower-Holders, of which the following is a specification.

This invention relates to an improved flower holder and has as one of its principal 10 objects to provide a device for carrying a rose, carnation or other flower upon a coat lapel while the lower end portion of the stem of the flower will be immersed in water so that premature wilting of the flower will be 15 prevented.

The invention has as a further object to provide a device of this character so constructed that water may not leak therefrom to soil or dampen the article of clothing to 20 which the device is attached.

A still further object of the invention is to provide means for removably securing the device to a coat lapel, which means will also tend to hold the closure cap of the receptacle 25 employed against distortion and thus maintain a close fit between the receptacle and the cap.

And the invention has as a still further object to provide a device of this character 30 which will be neat in appearance, will not be readily noticeable when in use, and which may be produced at minimum cost.

Other and incidental objects will appear hereinafter.

35 In the drawing;

Figure 1 is a perspective view illustrating the manner in which my improved holder is employed for supporting a flower upon a coat lapel, the lapel being shown in dotted 40 lines.

Fig. 2 is a sectional view of the device in position upon the rear of the coat lapel receiving the lower end portion of the stem of the flower, the lapel also being shown in section, and

45 Fig. 3 is a perspective view of the holder, the closure cap therefor being shown removed.

In carrying the invention into effect, I 50 employ a water receiving container or receptacle 10. This receptacle is adapted to be removably attached by an intermediate means to be presently described, to an article of clothing and may be made from glass or 55 any other suitable material. Near its upper end, the receptacle 10 is formed exteriorly

with an annular groove 11 and rising from said groove portion of the receptacle is a slightly reduced neck 12. Snugly but removably fitting over the neck 12 is a preferably rubber closure cap 13, the lower end portion of which will, when the cap is applied, bind in the groove 11 of said receptacle. As particularly brought out in Fig. 2, the upper portion of the cap is formed 60 with a conical wall defining at its base an annular shoulder 14 interiorly of the cap and when the cap is applied this shoulder overlies the upper edge of the neck 12 to closely contact therewith. A close and 65 water-tight fit will thus be formed between the closure cap and receptacle and possibility of leakage of water from the receptacle and consequent dampening or soiling of the article of clothing to which the receptacle 70 is attached eliminated. Formed in the top of the cap centrally thereof, is an opening 15 slightly enlarged toward its upper end and of a size to snugly but removably receive the stem of a flower therethrough. Accordingly, a flower stem may be pushed through said opening to project, as clearly indicated in Fig. 2, into the receptacle to be immersed 75 in the water contained therein. Since the opening 15 is relatively small and its wall 80 more or less snugly fits the stem of the flower, it will be seen that splashing of water from the receptacle through said opening will be prevented while at the same time the wall of the opening will grip the 85 flower stem for securely holding the flower 90 in position.

In order that the device may be attached to an article of clothing, I provide a pin 95 formed from a single length of suitable resilient material bent at one end portion to provide an eye 16 through which the length of material is passed forming a loop 17. The material of the pin is thence bent at substantially right angles to the loop to 100 form a shank or piercing prong 18. The loop 17 of the pin surrounds the closure cap 13 and, as clearly shown in Fig. 2, seats in an annular groove formed in said cap at the base of the conical wall thereof and in a 105 plane slightly above the interior shoulder 14 of the cap. The pin will thus be securely connected with the closure cap and further, as will be appreciated, by placing the loop 17 of the pin about the closure cap adjacent the plane of the shoulder, said loop 110 will act to reinforce the cap at this point

and prevent distortion of said shoulder so that a close fit may at all times be had between the cap and receptacle neck. Thus, said pin will perform the dual function of 5 providing attaching means for securing the device to an article of clothing as well as acting to reinforce the closure cap.

My improved flower holder is particularly designed for application to the rear side of 10 the lapel of a coat to be hidden thereby, and I have accordingly, in Figs. 1 and 2, so shown the device applied. In these figures, I have conventionally illustrated a coat lapel at 19, this lapel being provided with 15 the usual buttonhole. In use, the receptacle 10 of the holder is first filled with water and the closure cap 13 then fitted upon the neck 12 of the receptacle. The device may then be attached to the rear side of the lapel 19 a 20 suitable distance below the buttonhole there- in by forcing the shank or prong 18 of the pin into the material of the lapel and in this connection it will be noted by particular reference to Fig. 2, that a portion of said 25 material is engaged between the prong and cap to be gripped therebetween for firmly securing the device in position. The stem of a flower may then be inserted through the buttonhole of the lapel in the usual manner and thence directed through the opening 15 in the closure cap into the receptacle for immersing the lower end portion of the stem. Thus, the flower will be kept fresh and prevented from prematurely wilting. 30 35 At the same time, engagement of the wall of the opening 15 with the flower stem will prevent said stem from riding upwardly out of the receptacle to possibly result in loss of the flower.

Having thus described the invention, what is claimed as new is:

1. A device of the character described including a receptacle, a closure cap therefor provided with an opening to receive a flower stem projecting into the receptacle, and means engaged with the closure cap whereby the device may be removably attached to a garment. 45

2. A device of the character described including a receptacle formed with a mouth, 50

a closure cap constructed for the passage of a flower stem and snugly fitting over said mouth and formed interiorly with an annular shoulder to closely overlie the upper edge of said mouth and bind thereagainst, 55 and means connected with said cap whereby the device may be detachably secured to a garment.

3. A device of the character described including a receptacle formed exteriorly with 60 an annular groove and having a neck rising above said groove, a closure cap snugly fitting over said neck to bind at its lower end portion in said groove and formed interiorly with an annular shoulder to closely 65 overlie and bind against the upper edge of said neck, the cap having an opening for the passage of a flower stem, and means secured to the cap for detachably connecting said device to a garment. 70

4. A device of the character described including a receptacle, a stem receiving closure cap therefor, and means engaged with said closure cap for detachably securing the device to a garment and providing a reinforcement for the closure cap. 75

5. A device of the character described including a receptacle, a stem receiving closure cap therefor, and a pin looped about the closure cap and provided with a shank 80 for engagement with a garment whereby the device may be removably secured to said garment, the looped portion of the pin providing a reinforcement for said cap.

6. In a flower holder, the combination of 85 a receptacle, an elastic stem receiving closure cap fitting over the receptacle, and attaching means surrounding said cap to form a rigid band retaining the cap against stretching near the plane of the mouth of the receptacle.

7. A device of the character described including a receptacle, a closure cap therefor provided with an opening to receive a flower stem projecting into the receptacle, and a 95 pin engaged with the closure cap whereby the device may be removably attached to a garment.

In testimony whereof I affix my signature.
EDGAR D. HEGAMIN. [L.S.]
